UNITED STATES PATENT OFFICE.

BURNHAM C. STICKNEY, OF ELIZABETH, NEW JERSEY, ASSIGNOR TO UNDERWOOD
TYPEWRITER COMPANY, OF NEW YORK, N. Y., A CORPORATION OF DELAWARE.

TYPE-WRITING MACHINE.

1,139,080.

Specification of Letters Patent. Patented May 11, 1915.

Original application filed June 30, 1903, Serial No. 163,704. Divided and this application filed October 5, 1912. Serial No. 724,022.

To all whom it may concern:

Be it known that I, BURNHAM C. STICKNEY, a citizen of the United States, residing in Elizabeth, in the county of Union and State of New Jersey, have invented certain new and useful Improvements in Type-Writing Machines, of which the following is a specification.

This invention relates to typewriting machines, and particularly to so-called "visible" writing machines, in which the line of writing is always in view, and more especially to those of the "front strike" class; and is a division of my application No. 15 163,704, filed June 30, 1903.

My invention consists in certain combinations of devices, features of construction, and arrangements of parts, which will be hereinafter described and particularly 20 pointed out in the concluding claims; and it particularly relates to the case-shifting mechanism.

In the accompanying drawings, Figure 1 is a longitudinal sectional elevation of a 25 front strike writing machine embodying my improvements; one type action being shown in printing position, and the platen being shown in full lines in position for writing lower-case letters, and in dotted lines at 30 upper-case position. Fig. 2 is an elevation of the bell ringing mechanism. Fig. 3 is a front view with the carriage swung up. Figs. 4 to 6 are details of the margin mechanism.

The framework of the machine comprises 35 side walls and rear walls forming a base 1, and a depressed top plate 3. Forwardly extending type bars 4 are pivoted at their rear ends upon a curved fulcrum-rod 5 40 mounted in a segment 6, and strike rearwardly against a platen 7. The segment is radially slotted at 8 to receive the type-bar hubs. Each type-bar is provided with a lower-case type 9 and an upper-case type 45 10, the latter being uppermost when the type bar is in printing position, although this relation may be reversed within the scope of certain features of my improvements, and the type-bars may be otherwise mounted. 50 The type-bars may be operated by any suitable means, as for instance pull-links 11, extending rearwardly and downwardly from the type bars, pendent levers 12 connected between their ends at 13 to said links,

a horizontal rod 14 whereon said levers are 55 fulcrumed at their upper ends, horizontal links 15 connected at 16 to the lower ends of said levers and extending forwardly, and key-bearing bell-cranks fulcrumed upon a transverse rod 17 and having pendent arms 60 18 connected at 19 to said links 15, and forwardly-extending arms 20 bearing the keys 21. Returning springs as 22 may be provided for the type actions.

The platen 7 may be mounted by means of 65 an axle 25 upon a carriage 26, which may be of any suitable construction, but preferably comprises upper and lower bars 27 and 28, the former provided in its underside with a longitudinal groove 29, and the 70 latter in its upper side with a longitudinal groove 30; these bars being connected at their ends by upright bars 31 and 32 formed integral therewith. An integral plate or 75 bar 33 projects forwardly from said connected bars, and at its ends is formed with upright arms 34 and 35 in which the platen axle 25 is journaled. Embraced by the grooved bars 27 and 28 is a rail 36, set on edge and provided in its top and bottom 80 edges with grooves 37 and 38, which are provided with bearing balls 39, whereon the carriage runs. Said grooved rail 36 forms part of a movable frame, whereby the paper carriage is enabled not only to 85 run in letter-feeding direction, but also to move in a direction transverse thereto. This frame comprises, in addition to said rail (which may be otherwise formed in some cases) rearwardly extending integral arms 90 65, which are united at their forward ends by said rail, and a bar 66, which unites said arms between their ends and is integral therewith. Said arms are extended rearwardly from said bar 66, forming ears 67 95 and 68, which are hinged by pintles 69 in bosses 70 and 71 which project inwardly from the tops of the side walls of the framework 1. The carriage together with its supporting frame may be swung or tilted 100 up about said hinge, so as to expose the underside of the carriage. Said supporting frame, may, however, be otherwise formed and otherwise movably supported within the scope of my improvements.

Carriage-feeding mechanism is mounted upon the hinged carriage-supporting frame and coöperating with a rack 106 on the car-

riage; said feeding mechanism comprising upright detent and feeding dogs 107 and 108, the latter normally in engagement with the rack. The rack is mounted upon the 5 rear ends of hinged arms 109 and 110, the latter being prolonged forwardly of its hinge and provided with a depressible carriage-release key 111. The dogs are mounted upon one end of a rock-shaft 112, 10 journaled in a boss 113 formed upon an arm 114 directed upwardly and forwardly from the shifter-frame bar 66; and said shaft at its other end is provided with an operating arm 115, which at its rear end 15 is pivoted at 116 to a pendent link 117, whereby the arm is operated; said pivot 116 being normally substantially coincident with the axis of the hinge 69 of the carriage-supporting frame, so that the operation of 20 the escapement mechanism is substantially the same whether the frame is in normal position or shifted up to write capital letters. At its lower end said link is pivoted at 118 to the forward end of a rocker-arm 25 119, which projects forwardly from a horizontal transverse rock-shaft 120. A universal bar 121 is mounted upon the tops of a pair of arms 122 which rise from said rock-shaft, and lies in rear of the levers 12 of 30 the type-actions, so as to be operated thereby, the described universal-bar frame being provided with a returning spring 123.

The connection between the ribbon-vibrating mechanism and the escapement mechanism consists of a link 124, whose upper 35 end is pivoted to a forward extention 125 of the dog-rocker arm 115, and whose lower end is pivoted to a short arm 126 of the ribbon vibrator. By this means, whenever 40 the dog-rocker is vibrated by the keys, the vibrator is elevated to cause the ribbon to cover the printing point; and upon the return of the carriage-feeding mechanism to normal position, said vibrator drops to permit the ribbon to uncover the printing point. 45

The carriage may be propelled by a spring-barrel 127, lying horizontally and mounted upon the lower end of a stud 128 depending from the hinged carriage-frame; 50 a strap 129 being attached to the barrel and caught upon a hook 130 upon the carriage bar 28. A ratchet wheel 131 and pallet 132 are provided for adjusting the tension of the spring, the former having a finger-piece 55 133 and the latter a finger-piece 134, both of which in normal position project downwardly, the ratchet wheel and pallet being mounted below the spring-barrel. When the carriage is tilted up, access is given to the 60 ratchet wheel and pallet, thus facilitating the adjustment of the spring. By mounting the spring-barrel and the carriage-feeding mechanism upon the hinged frame, the latter is permitted to swing freely up and 65 down, without liability of deranging the

carriage-controlling devices, which always preserve their proper relation to the carriage.

Advantage is taken of the hinging of the carriage-support, to enable the latter to be 70 shifted up and down to enable different types to print. Normally the carriage and platen are in the lowermost position, as in full lines, thereby enabling the lower-case types 9 to print; while by elevating the carriage and platen, as indicated by the dotted circle 7, the upper-case types 10 are enabled to print. The downward movement of the carriage is limited by an adjustable stop 136, threaded forwardly through an arm 75 137 cast upon the rear wall of the machine framing; the ribbon-spool bearing arm 78 of the hinged carriage-supporting frame being prolonged below the ribbon-spool shaft, as at 138, to bear against said adjustable 80 stop. A shift-lever 139, bearing a key 140, projects forwardly and upwardly from a transverse horizontal rock-shaft 141, journaled in the side walls of the base; and about midway of its length said shaft is 85 provided with an upright arm 142, from which extends rearwardly a link 143, whose rear end has a sliding bearing at 144 in the upper portion of said cast arm 137. Said link is provided with a lug 145, adapted 90 to catch a nib 146 formed upon a hook-shaped stop 147 pivoted at 148 to the lower portion of said ribbon-spool carrying arm 78 in rear of the spool shaft. By depressing the shift key, the shaft 141 and arm 142 95 thereon are rocked, pulling forwardly the link 143, and by means of the lug 145 and nib 146 swinging the stop down, until said nib is arrested by a stop pin 149. Continued movement of the key, rock-shaft, arm and link 100 then swings the frame arm 78 forwardly and the frame and carriage upwardly about the hinge 69, until the parts are arrested, with the platen in the dotted line position, by the contact of the hook-stop 147 with the upper 105 end of said cast arm 137 (which of course may be provided with an adjustable stop, if desired). After the capital type or types are written, the shift key is returned to normal position by a spring 150, while the 110 hinged frame and carriage return by gravity. A spring 151 lifts the hook-stop 147 until it is again clear of the upper end of said cast arm 137, so that it may not contact therewith to interfere with the upward tilting movement of the carriage to the Fig. 1 position. During such tilting movement, the arm 78 and parts thereon are swung forwardly away from their coöperating parts mounted in the machine base; so that 115 at any time the carriage may be given either a limited movement for writing capitals, or a tilting movement to expose the underside thereof.

To provide for writing a line of capitals, 130

1 pivot at 152 upon said arm 137 a cam plate 153, whose forward edge, which is eccentric to the pivot, is adapted to engage a bearing-pin 154 projecting from the frame arm extension 138, so that by swinging said cam plate upwardly about its pivot, said arm is driven forward and the hinged frame and carriage elevated to the proper point for writing capitals. For operating said cam plate, I pivot thereto at 155, below the pivot 152, the rear end of a pull-link 156, which extends to the keyboard and is there pivoted at 157 to the upper end of a rock-arm 158, mounted upon a horizontal transverse rock-shaft 159 mounted between the walls of the framework. At the left-hand side of the keyboard an upright lever 160 is fixed upon said rock-shaft, so that a forward movement of said lever may lift the cam plate 153 to set the carriage to upper-case position. Forward and rear stops 161 and 162, the former preferably adjustable, may be provided for said lever; and a double-acting spring 163, adapted to bear against a pin 164 fixed upon the lever, may hold the lever against either stop.

The margin-governing mechanism, by which term is meant devices which either positively limit the travel of the carriage or warn the operator that the end of the line is approaching, or both, includes a rack 170, mounted beneath the carriage, being attached by screws 171 to the bottoms of arms or ears 172 depending from the carriage plate 33. Said rack is provided with a series of teeth 173, for enabling the tappets or stops to be fixed at different positions, according to the width of the left-hand or right-hand margin desired on the page of writing.

The means for limiting the return movement of the carriage, and thereby regulating the left-hand margin on the paper, comprises a box-like slide 174, fitted upon the rack and seen at the left-hand of the drawings, and having formed thereon a stop 175 projecting upwardly from the slide, and in position to contact with the forwardly projecting end of an arbor 176 mounted in the carriage-guiding rail 36 about midway of the length thereof, thereby to arrest the carriage. Said slide is provided upon its underside with a pawl 177, having an upwardly projecting tooth 178 for insertion in any of the notches in the rack, so that any desired width of left-hand margin may be secured. The pawl is provided with a handle 179 and a spring 180 for pressing the tooth 178 into engagement with the rack. By withdrawing the tooth, the slide and stop may be滑den freely along the rack in either direction. The pawl is pivoted vertically upon the slide at 181. The rack is provided upon its underside with a series of graduations 182, and the left-hand edge of the

slide 174 may be adapted to coöperate with said graduations, so that when said edge coincides with any graduation on the scale, the first letter of the line of writing will fall beneath the corresponding graduation on the platen scale 47. It will be observed that normally said slide, as well as other tappets upon said rack, is in an inaccessible position beneath the carriage, while the scale 182 is out of sight; but that upon tilting up the carriage, the scale is brought into full view, and ready access is afforded to the slide and its pawl, for adjusting the same along the rack. So far as this feature of my improvements is concerned, any suitable rack and other parts of margin-governing mechanism may be adopted, within the scope of my invention. The novel features pertaining to the margin-governing details herein shown are, however, preferred.

A bell 183, in rear of the rail 36, is hung by a strap 184 upon the bar 66 of the hinged carriage-supporting frame; and a clapper 185 is horizontally pivoted at 186 upon the rear side of said rail, normally resting upon a stop 187. The clapper is lifted by an arm 188, having a long bent finger 189 underlying the clapper, and secured by rivets 190 upon a head 191 formed upon the rear projecting end of the arbor 176, so that by rotation of the arbor, the arm 188 rises and lifts the clapper. It will be observed that the arbor extends horizontally through bosses 192 and 193 formed upon the rear and front sides of the rail, whereby a long bearing is given, to avoid binding. For rotating the arbor to lift the bell-clapper, a tappet 194 is mounted upon a slide 195 mounted upon the rack 170 and resembling the slide 174. Said tappet extends rearwardly from the top of a standard 196 rising from the forward edge of the slide; said standard clearing the forward end of the arbor 176, but said tappet being in position to engage a pallet 197 projecting upwardly from the tip of the arbor. During the letter-feeding movement of the carriage, the tappet engages the pallet and rotates the arbor, lifting its arm and the bell-clapper, until the tappet passes over the pallet, thereby releasing the same, and the bell clapper being left unsupported, falls and strikes the bell, to notify the operator that the end of the line is at hand. The slide 195 is provided with a pawl 198, having a rack engaging tooth 199 and a spring 200, whereby it may be adjusted along the rack, to regulate the right-hand margin upon the paper.

For locking the type-actions or otherwise rendering the keys ineffective to operate the types, I provide preferably upon the bell-controlling slide 195, a tappet 201, a short distance to the right of tappet 194, which lies close to the upper side of the slide, but projects sufficiently therefrom to engage a

pallet 202 provided upon the underside of the arbor 176, whereby the arbor is rocked in the opposite direction to that already described, thereby producing no effect upon 5 the bell-clapper, but swinging into effective position a tumbler 203, projecting upwardly from the head 191 of the arbor, and preferably integral with the arm 188. Said tumbler is thus brought directly beneath an 10 extension 204 projecting forwardly from the vibrating arm 125 of the carriage-feeding and ribbon-vibrating mechanism, thus preventing operation of said mechanism and hence of the universal-bar and the type- 15 actions. Normally said tumbler stands at one side of said extension 204, in which position it is maintained by a spring 205, coiled around a reduced portion of the arbor between its ends; said spring being of light 20 tension, and overbalanced by the weight of the bell-clapper, whereby the arbor is returned in one direction by the spring and in the other direction by the weight of the clapper. Said arbor 176 is slidably jour- 25 naled in said carriage-guiding rail, and its head 191 is engaged by the forked lower end of a rock arm 206, fixed upon a rock shaft 207 journaled at its end portions in brackets 208 projecting from the rear side of said 30 rail, and provided at its tips with buttons 209, whereby it may be turned. By this means the arbor may be drawn rearwardly to a sufficient extent to enable it to clear the tappets or stops mounted upon the rack 170, 35 thereby enabling a few more letters to be added at the end of the line, or enabling the carriage to run farther upon its return stroke, so that the first part of the succeeding line may be written in the left-hand 40 margin upon the paper. A spring 210 is provided upon the shaft 207, for returning the shaft, together with the arbor, to normal position.

A second or final key-locking tappet 211 45 may be formed upon the slide 195, at the right of the first line-locking tappet 201, this tappet operating in the same way as the tappet 201, and preventing the writing of any more letters at the end of the line. 50 In some cases, however, this tappet may be omitted. The slide 195 may be of sufficient length to accommodate the three described tappets, or if desired each may be mounted upon a separate slide. Upon its underside 55 the slide may be recessed, and the edge 212 of the recess may serve as an index to cooperate with the scale on the margin-gage rack, for setting the slide to ring the bell or lock the line at any desired point. 60 Each of the tappets, as well as the stop 175, is preferably formed upon its rear side with an oblique face, as 213 and 214, which during the usual carriage movements can back the arbor against the tension of the 65 spring 210, out of the path of the tappets or

stops, so that the latter are each effective in only one direction.

It will further be observed that the rod 57, which supports the collars 59, from which extend the paper-guiding fingers 56, 70 is mounted in a relatively inaccessible position below the platen scale and upon the underside of the carriage, so that when the carriage is in normal position, it is difficult to reach the collars to slide them along the 75 rod; but that when the carriage is tilted up, said collars are more accessible, and their adjustment is facilitated.

Variations may be resorted to within the scope of my invention, and portions of my 80 improvements may be used without others.

Having thus described my invention, I claim—

1. In a front strike typewriting machine, the combination with a segment supporting 85 a series of type bars each having a plurality of printing characters, and a platen, of a shift-lever, a platen shift frame mounted to oscillate up and down and having a rigid central arm arranged lower than the platen, 90 and connections whereby the shift-lever acts on said arm to shift the platen, substantially as set forth.

2. In a front strike typewriting machine, the combination with a main frame, the type 95 bars each having a plurality of printing characters, and a platen carriage, of a carriage-shift frame which is pivotally connected to the main frame at each side of its center to swing up and down and supports 100 said carriage, a shift-lever, and connections by which the lever acts on the center of the shift-frame to shift the platen, substantially as set forth.

3. In a typewriting machine, the combina- 105 tion with a main frame, a series of type bars, a platen, and a carriage for the platen, of a shift-frame supporting the carriage and ar- ranged transversely on the main frame and connected thereto by pivots at each side of 110 the center of the main frame and at the rear of the shift-frame, and a vibrating support connecting the central part of the shift- frame to the main frame, substantially as set forth.

4. In a typewriting machine, the combina- 115 tion with a main frame, a series of type bars, a platen, and a carriage for the platen, of a shift frame supporting the carriage and ar- ranged transversely on the main frame and 120 connected thereto by pivots at each side of the center of the main frame and at the rear of the shift frame, and a support connecting the central part of the shift-frame to the main frame.

5. In a typewriting machine, the combina- 125 tion with a main frame, a series of type bars, a platen, and a carriage for the platen, of a shift frame supporting the carriage and ar- ranged transversely on the main frame and 130

connected thereto by pivots at each side of the center of the main frame and at the rear of the shift frame, and a device extending from the central part of the shift-frame to 5 the main frame, and inclusive of a part vibratable to control the position of the shift frame.

6. In a typewriting machine, the combination with a main frame, a series of type bars, 10 a platen, and a carriage for the platen, of a shift frame supporting the carriage and arranged transversely on the main frame and connected thereto by pivots at each side of the center of the main frame and at the rear 15 of the shift frame, and a device capable of supporting said shift frame and extending from the main frame of the machine to said shift frame at a point about midway between the ends thereof.
- 16 7. The combination with a system of types, keys to operate them, and a platen, of a case-shift key, means operable by said key for effecting relative shift between the platen and the entire type system, a stop for 20 arresting said shifting means when shifted by the key, said stop normally out of operative position, and means for enabling the shift key to move the stop to effective position, preparatory to arresting the shifting means actuated by the key.
- 25 8. The combination with a system of types and a platen, of a case-shift key, case-shift mechanism operable by said key, a

stop for arresting said case-shift mechanism when shifted by the key, said stop normally 35 out of operative position, means for enabling said shift key to move the stop to effective position, preparatory to arresting said case-shift mechanism, and a permanent shift key having means for operating said 40 case-shift mechanism and maintaining it in shifted position while said stop remains in normal position.

9. The combination with a system of types and a platen, of a case-shift key, case-shift 45 mechanism operable by said key, a stop for arresting said case-shift mechanism when shifted by the key, said stop normally out of operative position, means for enabling said shift key to move the stop to effective position, preparatory to arresting said case-shift mechanism, and a permanent-shift key having 50 means for operating said case-shift mechanism and maintaining it in shifted position while said stop remains in normal 55 position; said case-shift mechanism being normally movable to and past its shift position while said stop remains in normal position, and being also movable beyond the position at which it is held by said permanent- 60 shift key.

BURNHAM C. STICKNEY.
